CLAIM

The ornamental design for an adjustable sand mold toy, as shown and described.

DESCRIPTION

FIG. 1 is a top perspective view of the adjustable sand mold toy showing my new design.

FIG. 2 is a bottom perspective view thereof.

FIG. 3 is a bottom plan view thereof.

FIG. 4 is a top plan view thereof.

FIG. 5 is a front elevational view thereof.

FIG. 6 is a rear elevational view thereof.

FIG. 7 is a left end elevational view thereof.

FIG. 8 is a right end elevational view thereof; and,

FIG. 9 is a perspective view showing the adjustable sand mold toy in an alternate position.
